(57) **CLAIM**

The ornamental design for a hair dryer, as shown and described.

DESCRIPTION

FIG. 1 is a first perspective view of a hair dryer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the hair dryer thereof;

FIG. 10 is a perspective view of another state of the hair dryer thereof; and,

FIG. 11 is an enlarged view of the selected portion 11 in FIG. 1.

The broken lines shown in the drawings depict portions of the hair dryer that form no part of the claimed design. The long dash/short dash broken lines in the drawings depict the boundaries of the enlarged views and form no part of the claimed design.

1 Claim, 11 Drawing Sheets
